VENDOR FOR BOTTLED BEVERAGES, OR SIMILAR ARTICLE

Richard T. Cornelius, Minneapolis, Minn., and E. Burton
Benjamin, Highland Park, Ill., assignors to The Cornelius Company, Anoka, Minn., a corporation of Minnesota

Filed July 3, 1962, Ser. No. 70,781

Term of patent 14 years

(Cl. D67—3)

FIGS. 6 and 7 are fragmentary perspective and side elevational views respectively, of a modified form of the vendor disclosed in FIGS. 1 to 5 inclusive; the remainder of this modified form is the same in appearance as the vendor shown in said views.

We claim:

The ornamental design for a vendor for bottled beverages, or similar article, substantially as shown and described.
